(57) **CLAIM**

The ornamental design for a color verification card, as shown and described.

DESCRIPTION

FIG. 1 is a perspective view of a color verification card showing my new design, wherein the color verification card is depicted in a closed position;

FIG. 2 is a front elevational view of the color verification card of FIG. 1, wherein the color verification card is depicted in the closed position;

FIG. 3 is a rear elevational view of the color verification card of FIG. 1, wherein the color verification card is depicted in the closed position;

FIG. 4 is a right side elevational view of the color verification card of FIG. 1, wherein the color verification card is depicted in the closed position;

FIG. 5 is a left side elevational view of the color verification card of FIG. 1, wherein the color verification card is depicted in the closed position;

FIG. 6 is a bottom plan view of the color verification card of FIG. 1, wherein the color verification card is depicted in the closed position;

FIG. 7 is a top plan view of the color verification card of FIG. 1, wherein the color verification card is depicted in the closed position;

FIG. 8 is a perspective view of the color verification card of FIG. 1, wherein the color verification card is depicted on its right side in an open position;

FIG. 9 is a bottom plan view of the color verification card of FIG. 1, wherein the color verification card is depicted in the open position;

FIG. 10 is a left side elevational view of the color verification card of FIG. 1, wherein the color verification card is depicted in the open position;

FIG. 11 is a rear elevational view of the color verification card of FIG. 1, wherein the color verification card is depicted in the open position; and,

FIG. 12 is a front elevational view of the color verification card of FIG. 1, wherein the color verification card is depicted in the open position.
